Application November 25, 1949, Serial No. 129,395

9 Claims. (Cl. 235—61.6)

1

This invention relates generally to record controlled accounting machines and more specifically to the accumulating mechanism thereof.

The principal object of the invention is to provide an accumulator arrangement wherein the speed of the adding operation thereof is increased over that of the prior art.

Another object of the invention is to provide an accumulator arrangement wherein the speed at which a principal digital value is accumulated is increased by breaking down the digital value into two components where one component is a multiple of a base divisor and the other component constitutes a remainder which is temporarily stored in a tube controlled relay circuit.

A further object of the invention is to provide an accumulator arrangement wherein part of the accumulator is responsive to the largest multiple of a base divisor that will go into a to-be-accumulated value as one component of that value, and the remainder as the other component of that value is stored in tube operated relay means.

A still further object of the invention is to provide a differentially movable accumulator wherein the multiples component and the remainder component are fused.

Another object of the invention is to provide a differentially movable accumulator wherein the largest multiple of a base divisor of one parent digital value is entered, while the remainder thereof is stored in relay means until the stored remainder is made equal to the base divisor, by the insertion of a second digital value having a remainder, when the sum of said remainder is then entered into the accumulator.

The present invention is directed towards a record controlled accounting machine wherein the speed at which the record cards are driven past the sensing brushes and the speed at which the sensed amounts are entered in the accumulator exceed considerably those speeds attained by the electrical accounting systems of the prior art. The improved results are brought about by coupling a tube controlled relay storage circuit with an accumulator similar to that shown by C. D. Lake in Patent No. 2,328,653 and filed April 1, 1941. The Lake accumulator is modified by changing the drive shaft gearing such that the speed thereof is one-half the speed at which the cards are driven past the sensing brushes and by adding an extra lobe to the carry cam, which lobe is displaced 180° from the standard lobe. Thus it is to be noted that when the drive shaft gearing is being driven at the

2

speed of the standard arrangement, as exemplified by the Lake accumulator, the speed of cards past the sensing brushes is double that of the standard arrangement. This difference between the card speed and the drive shaft gearing speed permits a clutch tooth of the accumulator to be present at pulse time for every even cycle point that is sensed, thus introducing into the accumulating operation a factor of 2 whereby, for every even cycle point of the machine, the accumulator may be moved one unit.

The electron tube controlled storage relay circuit is rendered effective whenever an odd amount is sensed in the record card. When a 15 perforation in the record card representing an odd amount is sensed, the largest multiple of the common base divisor or factor is entered into the differential element of the accumulator while the remainder thereof is stored in the 20 tube controlled relay circuit, with the multiple component and the remainder component being derived by dividing the divisor into the odd amount sensed. When a second odd amount is sensed during the next card cycle the remainder 25 thereof is applied to a second tube controlled relay circuit which deenergizes the first mentioned relay circuit and causes to be entered into the differential element of accumulator an amount equivalent to the sum of the two remainders, which sum is equal to the base divisor.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 represents a partially broken away side view of the accumulator unit.

40 Figs. 2 and 2a represent a circuit diagram embodying the principles of the invention with one of the orders shown in detail.

Fig. 3 is a timing diagram.

Accumulator

45 Referring to Fig. 1, there is shown a drive shaft gear 11 which is suitably geared to the main driving shaft (not shown) which, in turn, drives the record card feeding mechanism at the rate of speed such that the speed of the gear 11 is one-half that of the feeding mechanism or, to express the relationship in another manner, the gear 11 makes one-half revolution for each card cycle as shown in the timing diagram of Fig. 3. The gear 11 meshes with and

the lever 30a and enables the contact spring 23 to rock itself and lever 30a back to the normal position thereof.

Circuit diagram

The circuit diagram of Figs. 2 and 2a shows three denominational orders with the specific circuit arrangement of each order being similar to the tens order, which order is shown in detail. While only three orders are shown, it should be understood that the invention is not limited to such but is applicable to as many orders as are desired in a particular situation. The circuit diagram of Figs. 2 and 2a shall be described with reference to the arrangement of the tens order and in conjunction with Fig. 3 and upon an assumption that there is a perforation in the record card 1 for the tens order which represents the digital value 9. The record card 1 has a plurality of vertical columns with each column containing the usual index points 0-9 whereby an amount may be recorded in the card by making the appropriate perforation which, in the particular instant, is a 9 perforation representing the cardinal value 9.

During the interval the 9 perforation in the record card is being sensed, the normally opened contacts CB1 (Fig. 2a), (which close during each digit representing index point of the machine as shown in Fig. 3) close, thereby completing a circuit from the high side 2 of the main power supply to the low side 3 of the bias power supply system. The completed circuit may be traced from line 2, through line 5, the now closed contact CB1, the connecting line 6, the usual card lever contact 31 (Fig. 2), the conductive roll 1, through the sensed "9" hole to the brush 9 and the connecting plug wire 26 (Fig. 2a), through the normally closed carry relay point C1a, the selenium rectifier S1, the resistor R10 and the capacitor C1 to the line 3. At the relay point C1a, a second circuit is completed through the normally closed carry relay point C1c, the rectifier S2, the normally closed relay point R1a, the resistor R4 and the capacitor C2 to the line 3. The selenium rectifiers S1 and S2 are used in the grid feed lines of the gas tubes T3 and T1, respectively, for the purpose of preventing back circuits from one tube to another when the respective brush circuits are opened.

As the aforementioned closed circuits are made from the high side 2 to the low side 3, the capacitors C1 and C2 are charged as indicated in Fig. 3 thereby driving the respective control grids of the normally non-conductive gas tubes T3 and T1 above their normal firing point but which tubes still remain non-conductive inasmuch as the potential of their screen grids is below the firing point due to the normally open cam contacts CB2 and CB4 in the respective screen grid circuits of T3 and T1. By the proper selection of the magnitudes of the capacitors C1 and C2 and of the respective resistors R20 and R5 associated therewith, the grids of the non-conductive tubes T3 and T1 are maintained above the respective firing points thereof until "8" time such as shown in Fig. 3.

Between the sensing of the 9 and 8 positions in the card 1 the normally open cam controlled contacts CB4 close, as shown in the timing diagram of Fig. 3 (which contact closes just after the subsequent odd digit representing index points 7, 5, 3 and 1 in addition to closing just after the "14" index point), thus coupling the 75 screen grid of T1 with the high side 2 of the

drives the accumulator gear 12 at the speed ratio of 16 to 10. The gear 12 is fixed to the hub (not shown) of the drive clutch ratchet 13 with the gear 12 and the ratchet 13 each rotatably carried by the shaft 14. A disk 15 having ten teeth 15a disposed equally about the periphery thereof and a cam edge 15b is rotatably carried by the hub of the ratchet 13. A register wheel 16 having ten peripheral notches 16a which are adapted to cooperate with the upper end of the spring biased detent lever 17 is rotatably carried by the shaft 14. The register wheel 16 has ten rotative positions where each one-half revolution thereof is equal to five adding steps with each step being equal to a digital value of 2. The carry cam 18 is secured to the wheel 16 by a pair of pins 19-19, only one of which is shown and each of which projects from wheel 16 through openings in the disk 15 to a position adjacent the ratchet 13. One of the pins 19 pivotally carries the spring biased clutch dog 20 having integral therewith a clutch tooth 20a which is made to cooperate with the ratchet 13. The carry cam 18 has a pair of projections 18a disposed 180° from each other with each projection having a notch 18b adjacent thereto where each projection and notch associated therewith cooperates with the lug 21 in introducing a carry into the next higher order.

The functioning of the wheel 16 is controlled by the start magnet AM and the stop magnet SM in the usual manner as explained in detail in the G. F. Daly Patent No. 2,377,762. Whenever a perforation in a record card, which represents a particular value, is sensed the magnet AM is energized whereby the armature 28 is attracted thereto resulting in the clutch lever 22 being rocked in a counterclockwise direction thereby disengaging the clutch tooth 22a of the lever 22 from the tooth 15a of the disk 15 whereby the disk 15 is made free for rotation. Upon the release of the disk 15 from the clutch lever 22, the clutch dog 20 is rocked into engagement with the ratchet 13 and the wheel 16 is thereby clutched to the ratchet for rotation. After the largest multiple of the base divisor, which divisor is equal to a value of 2, has been entered into the wheel 16, the magnet SM is energized thereby rocking the tooth 22a of the clutch lever into engagement with the tooth 15a, such as shown in Fig. 1, thus preventing further rotation of the disk 15 whereby the clutch dog 20 is disengaged from the ratchet 13 and the wheel 16 is made free of the drive.

While the register wheel 16 is rotating due to the energization of the magnet AM the lug 21, for the rotative positions of 0, 2, 4 and 6 is riding upon the circular portion of the carry cam 18. After a value of "8" is entered in the wheel 16, the lug 21 falls into the notch 18b whereby the contact spring 23 engages the carry contact 8T as shown in Fig. 1, thereby conditioning the particular order for a carrying operation to the next higher order. When the wheel 16 advances to or past the "0" value position the projection 18a of the carry cam 18 will raise the contact spring 23 into engagement with the contact 10T and will rock the lever 30a into a position to be latched by the latch lever thereby holding the spring 23 against the contact 10T whereby a carry from a lower order to a higher order may be effected. After carry has taken place, a stud 11a extending from one side of the drive gear 11 rocks the latch lever 30 clockwise which, in turn, releases

main power supply resulting in the screen grid potential of the tube T1 being driven above the firing point thereof to render T1 conductive. Upon T1 becoming conductive, the plate of the tube T1 is coupled to the high side 2 of the power supply through the relay coil R1, the parallel circuit comprising the normally closed contact points R2a and the capacitor C4 and the conductor 5. The flow of current through the coil R1 energizes the coil whereby the contact points R1a and R1c are tripped to the other side while the contact point R1b is closed. At "8" time, the contacts CB4 open, thereby removing the potential from the screen grid of T1 without effecting the conducting of T1 inasmuch as once a gas tube is conducting the grids thereof cease to control the functioning of the tube until the tube is again made non-conducting. Likewise, at "8" time the cam controlled contacts CB2 close, as shown in the timing diagram of Fig. 3 (which contact closes at the subsequent even digit representing index points 6, 4 and 2 in addition to closing at the "14" cycle point), thereby completing the circuit between the high side 2 of the power supply system and the screen grid of the tube T3. Upon the closing of CB2 the screen grid of T3 is driven above the firing point thereof thereby rendering T3 conducting. With current flow being initiated in the tube T3, the accumulator add coil AM, which is in the plate circuit of T3, is energized whereby the clutch dog 20 due to the usual overlap or mechanical lag engages the ratchet 13 during the "7" index point thereby commencing the turning of the wheel 16. After "8" time and prior to "7" time the contacts CB2 return to open circuit thereby driving the plate potential of T3 below the firing point thereof and thus rendering it non-conductive, as shown in the timing diagram of Fig. 3.

The adding wheel will be advanced to the intermediate portion of the "11" cycle point where it is stopped due to an impulse being applied to the accumulator stop magnet SM upon the closing of the cam controlled contacts CB3 at "0" index time, as shown in Fig. 3. At the closing of contacts CB3 the circuit whereby the stop magnet SM is energized may be traced from line 2 to line 5, the magnet SM, the now closed CB3 and line 3.

Thus it is noted that, at this stage of the assumed problem, the parent cardinal number 9 has been split into two components where one component is registered in the accumulator wheel 16 and which component is the largest multiple of the common divisor, which is 2 (which is derived from the ratio of the speed of the gearing as pointed out previously), while the other component constitutes the remainder of the parent value and is stored in the relay coil R1 due to the energization thereof when T1 was made conductive. Thus with the adding wheel 16 having moved four units, the lug 21 has moved into the notch 18b of the carry cam 18 thereby rocking the contact spring 23 into engagement with the carry contact 8T whereby the circuit is conditioned for a carry operation. At "14" time the contacts CB6 close thereby initiating a carry pulse which is delivered to the accumulator circuit by means of line 27 but is ineffectual inasmuch as the contact point R2b is open due to T2 being non-conductive thus preventing the carry pulse from being applied to the circuit.

Now proceeding with the problem and carrying it one step farther, let it be assumed that the next record card to be sensed bears a "1" per-

foration which value is to be added to the digital value 9 of the previous record card. Upon the sensing of the "1" value in the card and in conjunction with the closing of CB1 at the "1" digit representing index point a first complete circuit is made from the line 2, the closed CB1, line 6, the card lever contact 31 (Fig. 2), the conductive roll 7, through the sensed "1" hole to the brush 9 and the connecting plug wire 26 (Fig. 2a) through the normally closed carry relay point C1a, the selenium rectifier S1, the resistor R10 and the capacitor C1 to the line 3 whereby the capacitor C1 is charged thereby increasing the grid potential of T3 above the firing potential thereof. As a result of CB2 being open at this "1" time in the cycle (see Fig. 3) and thus preventing the application of a potential to the screen grid of T3, the tube T3 remains non-conductive and the capacitor C1 discharges through the resistor R2. With the closing of CB1 a second circuit is also completed from the line 2 through to the line 3 by means of the closed contact CB1, line 6, the conductive roller 7, through the "1" perforation to the brush 9, the line 26, the contact C1c, the rectifier S2, the now shifted contact R1a (due to T1 being conductive), the resistor R7 and the capacitor C3, whereby the capacitor C3 is charged, resulting in the grid potential of the non-conductive gas tube T2 being raised above the firing potential thereof.

At one-half after "1" the cam controlled contacts CB4 close resulting in a potential being applied to the screen grid of the non-conductive tube T2 which drives the screen above the firing point thereof and renders T2 conductive. Upon T2 becoming conductive, a circuit is completed between the high 2 and low 4 sides of the power supply source through the normally closed contacts CB5 (which remain closed until the "15" index point), the coil R2 and the now conducting T2 whereby the coil R2 is energized resulting in the contact point R2a, which is in the plate circuit of T1, being opened while the contact point R2b is closed. With the opening of contact point R2a the tube T1 is rendered non-conductive thereby deenergizing the coil R1 and resulting in the contact points R1a, R1b and R1c being returned to the normal position thereof.

At "14" time the carry contacts C6 close, thus making the carry circuit whereby a carry pulse is initiated and the coil AC is energized. The carry pulse is applied to the control grid of the non-conductive tube T3 through line 27, the now closed contact point R2b, the shifted contact point C1b, the rectifier S1 and the resistor R10 thus driving the control grid of T3 above the firing point thereof. Simultaneous with the initiation of the carry pulse, the contacts CB2 are closed whereby a potential is applied to the screen grid of T3 which raises the potential thereof above the firing point thus rendering T3 conductive. With T3 being made conductive, the start magnet AM which is in the plate circuit of T3 is energized thus producing rotation of the adding wheel 16 which commences, due to the over-lap between the clutch dog 20 and the ratchet 13, during the "15" time. Likewise, during the initiation of the carry pulse a carrying operation will take place to the next higher order due to the condition of the R2b contact and the 8T carry contact and which operation shall be described subsequently. The tube T2 is restored to a non-conductive status when the contacts CB4 and CB5 open respectively during the "14" and "15" index point. At "16" time a knock off

Impulse is delivered to the coil SM by the closing of CB3 whereby the rotation of the wheel 16 is stopped after one unit, which is equivalent to a digital value of 2, has been entered therein. Thus it is to be noted that the remainder component of the preceding cycle as represented by a digital value of "1," and the cardinal number "1" which was sensed in a subsequent cycle were stored together temporarily in relays and then transferred to the accumulator at carry time to be entered therein.

Carry operation

Let it be assumed, for example, that the register wheel for the units and tens order are both in the 8 value position with an odd count stored in the relay circuit R1 of each order. With the wheels in the 8 value position, the contact spring 23 of each order is in engagement with the carry contact 8T. Likewise, with the relay circuit R1 energized, the contacts R1a, R1b and R1c have all been tripped from the normal position thereof. Now, when a value of "1" in the units order is sensed in a subsequent record card, the tube T2 of the units order is rendered conductive and T1 of the units order is made non-conductive whereby the sensed value is stored in the relay R2 as pointed out previously.

The carry operation is initiated in the "14" cycle point by the closing of the contacts CB6 whereby a source of potential is applied to the carry circuit resulting in the energization of the coil AC which causes the carry relay points C1a and C1c to be tripped to the respective points thereof C1b and C1d. During this operation, a carry pulse is applied from the line 2 through the carry circuit and coil AC, line 27, the now closed contacts R2b and R1b to the grid of the non-conductive tube T3 thereby driving the grid above the firing point potential. Simultaneous with the application of the pulse to the grid of T3, the contacts CB2 close thereby driving the screen grid of T3 above the firing potential thereof and resulting in T3 being made conductive. Upon being made conductive the coil AM is energized thereby permitting the register wheel to move to the "0" position as pointed out previously. Inasmuch as the carry contact 8T of the units order is in a closed position the carry operation may be carried further to the next order in succession, which is the tens order. In this instance the carry pulse is applied from line 27, the closed R2b of the units order, the 8T contact of the units order, the line 28 which feeds the pulse from the units order to the tens order, the shifted C1d of the tens order, the rectifier S2, the now shifted R1a to the grid of the non-conductive tube T2 which is subsequently rendered conductive and non-conductive before the end of the card cycle. The carry over from the units order is also applied through the contact R1b of the tens order, which is now closed due to the tube T2 associated therewith being conductive, contact C1b of the tens order, to the grid of the tube T3 of the tens order which is rendered conductive in the manner pointed out previously thereby energizing the magnet AM and permitting the wheel to shift from the "8" position to the "0" position. Inasmuch as the carry operation moves the register wheel of the tens order from the "8" to the "0" position, unity must be carried further to the next denominational order in succession which is the hundreds order. In the hundreds order the contacts R1b and R2b are both open while the tubes T1, T2 and T3 are non-conductive. The carry 75 thereof.

over from the tens order is applied to the hundreds order by way of the closed 8T contact of the tens order, the line 28 connecting the tens and hundreds order, the shifted contact C1d, the rectifier S2, the contact R1a to the grid of the non-conductive tube T1. At one-half after the 14 cycle point the contact CB4 closes rendering T1 of the hundreds order conductive and resulting in the storing of the unity carry over in the 10 relay R1 associated therewith.

Another problem which demonstrates the operability of the accumulator centers around the adding of two even numbers which are sensed from two separate cards. This problem will be 15 described with reference to the arrangement of the tens order and it shall be initially assumed that there has been entered in the register wheel 16 of the tens order a value of 6 and that a subsequent record card contain an 8 perforation in the 20 tens order. During the interval the 8 perforation in the record card is being sensed, the normally opened contacts CB1 and CB2 close, as shown in Fig. 3, whereby the tube T3 is rendered conductive in the manner as referred to previously. Likewise, as pointed out previously, upon the sensing 25 of the 8 perforation in the card the capacitor C2 of the tube T1 is charged thereby driving the grid potential thereof above the firing point but this charge drains off before the contacts CB4 apply 30 a potential to the screen grid of T1 thus preventing the tube T1 from being rendered conducting.

With the tube T3 being made conductive the start magnet AM, which is in the plate circuit of 35 T3, is energized whereby the clutch dog 20 engages the ratchet 13 and the wheel 16.

While the wheel 16 is rotating and adding the value 8 to the already entered value of 6, the carry 40 wheel passes the 0 value on 9 the projection 18a of the carry cam cams the lug 21 in an upward direction so as to force the spring contact 23 into engagement with the 10T contact. After the wheel has moved 2 units, which is equivalent to a value 45 of 4, past the 0 value, the contacts CB3 close at "0" index time thus energizing the stop magnet SM whereby the wheel 16 is stopped.

At the "14" time the contacts CB6 close thus 50 completing the carry circuit whereby a carry pulse is initiated and the coil AC is energized. The carry pulse is applied to the tens order through the line 27 where it is coupled to the 10T contact through the medium of the connecting line 32. From the 10T contact the carry 55 pulse is applied to the hundreds order by the line 28 where the circuit may be traced through the elements of the hundreds order comprising the closed contact point C1d, the rectifier S2, the contact point R1a to the capacitor C2 and finally line 3. Upon the application of the pulse to C2, a charge is introduced therein which drives the grid of T1 above the firing potential thereof. Simultaneous with the release of the carry pulse, the contacts CB4 close whereby a potential is 65 applied to the screen grid of T1 resulting in the igniting of T1 and energizing the coil R1 whereby the odd count, resulting from the addition of the values 6 and 8, is stored therein indefinitely.

At "16" time one of the studs 11a disposed upon the gear 11 rocks the latch lever 30 (see Fig. 3) which, in turn, releases the lever 30a and enables the contact spring 23 to rock itself and the lever 30a back to the normal position.

Readout means

During the aforementioned adding operation, the brush of the emitter 24, which is of conventional construction, is rotating constantly at a speed which is equal to the speed of the card feeding mechanism and which is twice the speed at which the gear 11 is being driven. Whenever a total printing is desired the switch 33 is closed which thereby couples a source of potential 34 to the emitter 24 such that as the brush of the emitter 24 rotates it successively connects the contacts R1c, through the medium of the lines 25, to the potential 34 thus impressing digital impulses on the print magnet PM at the appropriate time for the entry therein of corresponding digits in the accumulator.

The numbered segments of the emitter 24 are coupled to the corresponding numbered contact points R1c. The contact points R1c are paired with each odd numbered contact point and the adjacent lower numbered point being paired with each pair of points being selectively coupled through the corresponding contacts 35 to the segment of the accumulator commutator 29 which represents a value equal to the lower numbered contact point of each pair of points. The selecting of the contact points R1c is controlled by the relay coil R1 which upon becoming energized, due to the tube T1 being made conducting, trips the movable contact 35 between each pair of contact points from the even numbered points, which is the normal position of the contact 35, to the odd numbered points.

Now assume for example that a total printing is desired after a group of cards has been sensed and that there has been entered in the accumulator a value of 9. Under this assumption the brush of the counter commutator will be in contact with the 8 segment thereof while the coil R1 will be in an energized state due to the storage therein of the odd count in a manner as pointed out previously. With the coil R1 in an energized state the contacts R1c are tripped from the even numbered points to the odd numbered points. The accumulator is now in condition for a printing operation which may be brought about through the closing of the switch 33. When the switch 33 is closed a complete circuit for printing will be made from the source of potential 34, the closed switch 33, the brush of the emitter 24, the 9 segment of the emitter, line 25, the 9 contact point of R1c to the contact 35 associated therewith, the 8 segment of the commutator 29, the brush of the commutator in contact with the 8 segment, and finally from the brush to the print magnet PM. With the energization of the print magnet PM, the printing operation may be effected in a well known manner, as disclosed for example, in U. S. Patent No. 2,377,762 where the recording magnet RM (Fig. 11c of the patent) operates similarly to applicant's magnet PM.

While the invention is described with reference to a printing operation it should be noted that the readout may be used for other purposes such as is well known in the art.

Resetting of the accumulator may be effected in a known manner, such as for example by adding thereto the tens complement of the total standing therein which will advance the wheels to represent zero in all orders.

While there have been shown and described and pointed out the fundamental novel features of the invention as applied to a preferred embodiment, it will be understood that various

omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a cyclically operable machine of the class described having means for feeding record cards in which designations represent the digits of an amount in cardinal notation form, means for sensing said record cards, accumulator means having a plurality of denominational ordered accumulating elements, carry means for coupling said elements, electron tube controlled storage means operably connected to each of said elements, means controlled by said sensing means for entering into each of said elements, the largest multiple of a common divisor where said multiple is the result of dividing said divisor into said sensed amounts, further means controlled by said sensing means for entering into said storage means the remainder component of said amounts, said remainder being retained in said storage means, means effective upon entry of a second remainder component in said storage means for entering the sum of said remainders as a unit in said accumulating elements, the sum of said remainders being equal to said common divisor.

2. In a cyclically operable machine of the class described, means for feeding record cards bearing designations of the digits of an amount in cardinal notation form, means sensing said cards in succession, accumulating means including a plurality of denominational ordered accumulator elements, carry means operatively connecting said elements, means for entering in said elements a component part of said sensed digits, electron tube controlled storage means operatively connected to each of said elements, means for entering in each of said storage means the remainder component of said sensed digits, said component part and said remainder component being derived by dividing said digits by a common base divisor.

3. In a cyclically operable machine of the class described, a plurality of record cards each having a plurality of denominational ordered columns bearing amounts designated therein in cardinal notation form, means sensing each of said columns for the digital value entered therein, each of said sensing means having accumulator means operably coupled thereto, each of said accumulator means having an accumulating element and an electron tube relay controlled storage means coupled thereto, means for entering in said elements the largest multiple of a base divisor as one component of said digital value, means for entering in said storage means the remainder component of said digital value, said largest multiple and said remainder being derived from said digital value by dividing said digital value by said divisor, readout means coupled to each of said accumulators, said readout means constructed and arranged to read out the totals only of said columns.

4. In combination, an accumulator having an accumulating element adapted to accumulate a first component of a digital value in cardinal notation form, electron tube relay controlled means adapted to store therein a second component of said value, said controlled means being operably coupled to said accumulating element,

said first and second components being derived by dividing said digital value by a common base divisor, said first component being the largest multiple of said divisor while said second component constitutes a remainder of said divisional operation, said accumulator having a readout commutator coupled thereto, said readout commutator causing to be read out the sum of said first and second components.

5. In combination, an accumulator having an accumulating differential element, first, second and third electron discharge devices, said devices normally being non-conductive, said element being controlled by said first device, a first relay means being controlled by said second device, a second relay means being controlled by said third device, a first means energizing said first device thereby activating said element whereby the largest multiple of a base divisor is entered in said element, a second means rendering said second device conductive thereby energizing said first relay means whereby a remainder component is stored therein, said largest multiple and said remainder being derived by dividing said divisor into a first digital value, means rendering said third device conductive thereby energizing said second relay means whereby a remainder from a second digital value is stored therein, said first relay means being made inactive upon said second relay means becoming active, means for entering in said element the sum of said remainders, and means for rendering inactive said second relay means.

6. A cyclically operable machine of the class described comprising record cards bearing designations of the digits of an amount, means successively sensing said cards for said digits, means for deriving from each of said digits a first and second component, said first and second components being obtained by dividing each of said digits by a common base divisor, said first component constituting the largest multiple of said division while said second component constitutes a remainder, an accumulator means having an accumulating element and a relay storage means, said storage means coupled to said element, said largest multiple being entered in said element, said remainder being stored in said storage means, a readout commutator operably coupled to said accumulator, said commutator adapted to read out the sum of said first and second components.

7. A cyclically operable machine of the class described comprising a differentially movable element having five numbered rotative positions of 0, 2, 4, 6 and 8, whereby the multiples component

of a sensed digital value is entered therein, electron tube controlled relay means for storing the remainder component of said value, said multiples and remainder components being derived by dividing said value by a common base divisor, said relay means being associated with said element, means operably coupled to said relay means for modifying the significance of said positions whereby said positions will be adapted to read out a value one greater than said position.

8. In a machine of the class described having means for cyclically feeding record cards in which designations represent the digits of an amount in cardinal notation form, said card feed cycle having an entry period and a carry period, means for sensing said record cards, a movable adding element to receive the largest multiple component of a sensed digital value, a first electron tube controlled relay means for receiving the remainder component of said value, said element and first relay receiving said components during said entry period, a second electron tube controlled relay means operably coupled to said first means, said second relay being energized during the entry period of a subsequent sensed value having a remainder component if said first relay is energized, means controlled by said second relay for entering the sum of said remainders into the adding element during the carry period.

9. A movable accumulating wheel having five rotative positions of 0, 2, 4, 6 and 8 for entering therein the largest multiple of two of a sensed digital value, a first relay means for storing the odd remainder component of said value, said first relay means being operably associated with said element, a second relay means operably coupled to said first relay means, said second relay means adapted to store the odd remainder component of a subsequent sensed value, means for advancing said wheel one position during the carry period concurrently with the tens carry to the higher order when said second relay has stored therein said subsequent odd remainder.
